AUTOMATIC RECOIL FOOT ADJUSTING DEVICE

Arthur Morgan, Port Jervis, N. Y.

Application July 18, 1935, Serial No. 32,085

5 Claims. (Cl. 128—25)

This invention relates to a novel appliance or device for conditioning and reconditioning mal-positioning of certain bones in the transverse and longitudinal arches of the human foot and has 5 reference in particular to a manually manipulated and controlled mechanical structure of a resilient pressure resistant recoil type. By way of introduction and without attempting to give a scientific survey of the need for a device of this classification I would say that a fundamental cause of a great majority of foot trouble lies in the mal-positioning of certain bones, especially in the transverse arch and the correction lies in the adjustment of these bones back to normalcy. The 10 test of normalcy in the arch rests not in the height of the arch but rather in the correct relative positioning of its component bones, complementary ligaments and companion structure.

I have found it expedient and practicable to accomplish reasonable and reliable results through 20 the adoption and use of a simple, economical and reliable device which when correctly employed can be used to great benefit by adjusting to proper relationship the transverse tarsal arch, the longitudinal arch, as well as the individual bones of the tarsal, meta-tarsal and phalangeal articulations of the foot, and which is also susceptible of operation to reposition their contiguous muscles and ligaments attending the breaking down of adhesion.

Or otherwise stated, I have evolved and produced a satisfactorily usable foot pressed spring returned device which is calculated for use under the supervision of a doctor, or in the hands of a skilled patient to obtain relief from ankle weakness and strains and pains attendant upon misplacements and pressure upon nerves, whereby to quicken and increase the functional activity of the blood vessels and to thus hasten the passage of 30 toxic materials into the blood.

Briefly described, the preferred embodiment of the invention comprises a base including properly encased spring pressure resistant means cooperable with properly allocated cushioning pads, together with a manually depressed unit having members engageable with the pressure resistant means and having means at its top to provide an appropriate foot rest calculated to promote a properly adapted comforting adapter or form for 40 the foot.

Other features and advantages will become more readily apparent from the following description and drawings.

In the drawings:

Figure 1 is a view in section and elevation show-

ing the preferred embodiment of the invention as constructed in accordance with my own inventive ideas.

Figure 2 is a transverse section looking at the structure in a direction from right to left in Figure 1.

Figure 3 is a diagrammatic view showing the manner in which the same foot rest shown for example in Figure 2 is utilized for arch adjusting purposes by merely placing the foot at right angles 10 to the longitudinal dimension of the foot rest, the figure showing at the left an adjustment for the tarsal arch and showing at the right in dotted lines the method of adjusting the meta-tarsal phalangeal articulations.

Figure 4 is a view similar to Figure 1 disclosing how the foot is placed on the foot rest for adjusting the longitudinal arch.

Figure 5 is a view similar to Figure 4 showing the foot in a position for adjusting the phalanges.

In reducing the invention to practice, I have found it practicable and feasible to utilize a base of the type indicated in Figure 1 by the numeral 6. This is in the nature of a wooden box or similar housing or enclosure and includes a baseboard 7 and a suitable top or plate 8. This plate is provided at longitudinally spaced points with openings and properly shouldered bushings or guides 9 are fitted in the openings. The lower threaded ends of the bushings are maintained in assembled position by retaining nuts 10. These bushings serve as guides for the reciprocatory perpendicularly disposed plunger rods 11. These are of duplicate construction and slide down into the interior of the box through the guide bushings 9. Suitable heads 12 are provided on the lower end and are designed to come down into quick impact relation with the rubber bumpers or cushions 13 located in the box. The pressure resistant means as a unit is preferably in the nature of mechanical spring devices and includes a pair of oppositely extending U-shaped frames or yokes 14. The bight portions of these are engageable with the heads 12 and the arms are formed with eyes pivotally surrounding the horizontal supporting pins 15.

The pins in turn are supported by way of lugs or ears 16 on adapter brackets. These brackets are of general L-shaped form and include upstanding plate portions 17 and attaching base portions 18 fastened in the box. The two brackets are arranged in abutting relationship so as to accommodate the companion arrangement of the pivoted downwardly swingable yokes 14. The plate portions of the brackets serve as abutments for the ends 19 of the torsional springs 20. The

coiled springs 20 surround the aforesaid pins 15 and have extensions 21 engaging the arms of the yokes 14. This normally keeps the yokes up into contact with the heads 12 and raises the pins 11 up to the position shown in Figure 2 which is the normal position ready for use.

Different types of foot rests may be detachably connected to the upper ends of the plunger rods or pins 11. That is to say, these forms or foot rests will be expressly shaped and thus adapted to individual needs and requirements. Therefore, the term "footrest" is intended to cover, generically speaking, the arrangement shown in Figure 1 as well as the diversified arrangements fundamentally the same. In Figure 1, the form or foot rest 22 comprises a U-shaped connecting unit whose intermediate portion 23 is separably joined to the upper ends of the pins 11. The upstanding ends 24 and 25 are constructed to 20 accommodate the laterally bent down-turned ends 26 and 27 of the adapter member. This member is in the form of rigid metal strip channel-shaped in cross section and having a compound curve, that is, complementary bends 28 and 29. The end 26 is preferably rigidly bolted to the adjacent portion 24 while the end 27 is adjustably connectible with respect to the upstanding part 26 and this permits a limited degree of adjustment to be made for elevational purposes.

It is to be pointed out here that the unit comprising the part 22 and its associated feature 23 constitutes a fixture such as might well be collectively referred to as a foot rest. The part 22 being separable can be varied so far as longitudinal and transverse contour is concerned. The part 23 is standardized and these differently shaped parts 22 will therefore be interchangeable. Or stated otherwise the parts 22 will be made for individual needs according to prescription. It is evident, however, that from a fundamental structural standpoint, this foot rest means is detachably connectible with the reciprocating pins or rods 11 and that it may be used in the different manners or ways shown in Figures 3, 4, and 5. For example, in Figure 4 we see the device in use for making an adjustment to the longitudinal arch. In Figure 3, we see the foot plate at right angles to the longitudinal dimensions of the foot rest for making two distinct 40 adjustments. For example, in full lines in the left in Figure 3, the tarsal arch only is being adjusted. At the right as shown in dotted lines the meta-tarsal phalangeal articulation is being compensated for. Finally, in Figure 5, we see 50 the position of the foot for the adjustment of the phalanges and it will thus be discerned that the same style or type, structurally speaking, of foot rest is more or less universally employed for making the various foot adjustments.

In order to operate the device, the patient stands erect with the recoil adjuster on the floor, with the naked or stocking covered foot resting lightly upon the foot rest. The position of the foot in relation to the foot rest will vary according to the particular treatment or need in hand. That is to say, either the toe portion or heel portion will be properly related with respect to the foot rest according to the foot adjustment to be made. I shall not, therefore, go into the diversified diagrammatic illustrations of the various foot positions with respect to the foot rest. All that is seemingly necessary to say is, that with the foot properly positioned on the foot rest, by using a snappy downward thrust 70 into the foot rest, by using a snappy downward thrust 75 the resistant mechanical mechanism is brought

into play. The thrust should be that of a light blow, quickly released as the user feels the impact of the heads on the plunger rods striking the rubber bumpers in the bottom of the box. In practice it has been found advisable to utilize 5 three or four successive thrust movements one after the other. The foot is not released after the first thrust but holds its relative position ready to give the second, third, and so on. The spring means in the box acting on the plunger 10 rods keeps them under resilient stress, that is, constantly pushed upwardly. Thus, not only is it necessary to force continuously downward, but it is necessary to lift the foot up with the foot rest against the tension of the spring return 15 means and it is this constant pressure resistant means which accomplishes the result desired.

It is thought that persons skilled in the art to which the invention relates will be able to obtain a clear understanding of the invention 20 after considering the description in connection with the drawings. Therefore, a more lengthy description is regarded as unnecessary.

Minor changes in shape, size and rearrangement of details coming within the field of invention claimed may be resorted to in actual practice, if desired.

Having thus described the invention, what is claimed as new is:

1. In a structure of the class described, a hollow box-like base, brackets mounted in said base, a pair of oppositely disposed U-shaped yokes mounted on said brackets, spring means associated with the brackets and yokes for normally holding the yokes upwardly and resisting the 30 downward swinging movements, said base being provided with vertical guide bushings, a pair of duplicate rods perpendicularly slidable through said guide bushings into the interior of the box, the lower ends of the rods being formed with 35 heads engageable with said yokes, cushioning means in the box beneath said heads, and foot form adapter and rest means connected with the upper ends of said rods.

2. In an automatic recoil foot adjusting device 45 of the class described, a base provided with a pair of vertical guide bushings, a pair of duplicate complementary plunger rods, slidable in said bushings and having their lower ends projecting into the base, stop and cushioning elements in 50 the base located beneath the inner ends of said plunger rods, pressure resistant spring means in said base separate from said rods and stops, said spring means being interposed between the inner ends of the rods and said stops, and unitary 55 foot adapter means connected to the upper ends of said plunger rods.

3. In an automatic recoil foot adjusting device 60 of the class described, a base provided with guide means and spring means, a foot accommodation unit comprising rods slidable in said guide means and cooperable with said spring means, a U-shaped connector secured to the upper ends of said rods, and an adapter unit adjustably connected with said U-shaped connector, said 65 adapter being in the form of a horizontally elongated plate possessing a compound curve to render it adaptable to the human foot.

4. As a component part of a structural assemblage of the class described, foot accommodation means comprising a unitary assemblage embodying a pair of duplicate rods adapted to be mounted for reciprocation in a complementary base, a substantially U-shaped connector fastened to the upper ends of said rods, the end 70 75

portions of said U-shaped connector being bent upwardly in substantially perpendicular directions, and a companion adapter comprising a plate having a compound curve and depending 5 end portions adjustably connected with the end portions of said U-shaped connector.

5. As a component part of a structural assemblage of the class described, a hollow box-like base, brackets mounted in said base, a pair of

oppositely disposed U-shaped yokes, mounted on said brackets, spring means associated with the brackets and yokes for normally holding the yokes upwardly and resisting the downward sliding movements, said base being provided with 5 vertical guide openings and internal cushioning elements located beneath and in alignment with said openings.

ARTHUR MORGAN.
